UNITED STATES PATENT OFFICE.

HOMER A. WOODS, OF INDIANAPOLIS, INDIANA

LANTERN.

1,232,642.

Specification of Letters Patent. Patented July 10, 1917.

Application filed November 29, 1915. Serial No. 33,931.

To all whom it may concern:

Be it known that I, HOMER A. Woods, a citizen of the United States, residing at Indianapolis, in the county of Marion and State of Indiana, have invented a new and useful Lantern, of which the following is a specification.

It is the object of my invention to provide a portable self-contained electric lantern which holds the cells of the battery firmly in place, both against relative shifting and against accidental dropping out if the lamp is inverted, and insures that the connections are always made properly when the cells are changed; and which has such a battery connection arrangement for a two cell lantern that accidental short circuit of any cell, as by reason of a connection between two similar elements of the two cells, such as might be caused by the outer or zinc elements both coming into engagement with the casing, is impossible.

The accompanying drawings illustrate the various novel features of my invention. Figure 1 is a plan view of an electric lantern constructed in accordance with my invention, with the cover removed; Fig. 2 is a central vertical section through the upper portion of such lantern; Fig. 3 is a perspective view of the complete lantern; Fig. 4 is a front view of the switch construction, taken from inside the lantern casing; Fig. 5 is a section on the line 5—5 of Fig. 4; Fig. 6 is a detail of the connection between the switch and its operating handle; Fig. 7 is a section on the line 7—7 of Fig. 4; Fig. 8 is a reduced view showing the support of the dry cells on an insulating plate at the bottom of the lantern casing; and Fig. 9 is a detail of one end of the carrying bail.

The casing 15 is shown of proper size and shape to receive within it two ordinary dry cells 16 and 17, placed side by side, though my invention is not limited to a two-cell lantern save where expressly stated; and is conveniently made of sheet metal, preferably with a lining of corrugated paper 18 at the bottom for the dry cells to rest on. Such corrugated paper 18 insulates the outer or zinc elements of the two cells from the bottom of the casing 15 in case the dry cells are used without insulating casings of their own. The two dry cells are placed in the casing 15 in the positions shown in Fig. 1, so that the binding posts 20 and 21 which are provided on the respective zinc elements of

such cells may project through holes located as indicated in Fig. 1 in a loose insulating plate 22, which is provided with metal bushings at such holes for fitting over the binding posts 20 and 21, which metal bushings clamp in place metal terminal members 24 and 25 so that such terminal members are fixed on the insulating plate 22. The insulating plate 22 insures the proper positioning of the cells 16 and 17, and prevents them from shifting relatively to each other, such insulating plate extending nearly from front to rear of the casing 15 and overlapping upon both cells 16 and 17.

The lamp 39 and its reflector 45 are mounted in the front of the casing 15, in a reflector housing 27 which is also mounted on the front of the casing 15, the housing and casing being separated by an insulating washer 28. On the inside of the casing 15 and behind the reflector housing 27 are two insulating plates 29 and 30 which are clamped to the casing by a flanged metal sleeve 33 suitably insulated from the casing, as by an insulating bushing surrounding it. The flange 34 of the sleeve 33 fits within a cup-shaped terminal member 36, and the interior of said sleeve is threaded to receive the threaded base 38 of the incandescent bulb 39 which furnishes the illumination, so that by the interengagement of the threads one terminal of the bulb is connected to the terminal 36. The other or central terminal contact of the bulb projects through and beyond the sleeve 33 into engagement with a spring contact 41, which, together with a connection terminal 42, is clamped to the rear insulating plate 30 by a single rivet 43. The upper end 44 of the spring contact 41 is bent over the end of the plate 30 so as to prevent turning of the spring contact on the rivet 43 and thus insure that the free end of such contact is always behind the hole 26.

Against the inner face of the rear of the casing 15 are two superposed insulating plates 55 and 56, which, together with the rear of the casing 15 and the cross bar 57 of a rear carrying handle 58 are registeringly horizontally slotted to receive a link 59 of insulating material which is pivoted at one end to the upper or moving end of a switch lever 60, pivoted by a pivot rivet 61 to the insulating plate 56 near the lower end thereof. The cross bar 57 is backed by a slotted guide plate 62 through the slot of which extends the stem 63 of a switch-op-

erating knob 64, which is held in place to slide along the slot in the guide plate 62 by a washer 65 which is riveted to it on the opposite side of the plate 62 from the knob 64. 5 The stem 63 is continued as a pin 66 which projects freely through a hole in the link 59. By sliding the knob 64 along the slot in the guide plate 62, the switch lever 60 is swung about its pivot 61, but because of the free 10 connection between the pin 66 and the link 59 there is no tendency to twist the switch lever 60 no matter how much the knob 64 is tilted, and thus any binding of the switch lever 60 is avoided. The insulating plates 15 55 and 56, the cross bar 57, and the guide plate 62 are all riveted to the casing 15 by rivets 67, extending through all such parts. The switch lever 60 has a cup-shaped depression 69 which in the two positions of the 20 switch may fit over two rivets 70 and 71 respectively. The rivet 70 is connected by a thin metal contact strip 72 to a contact terminal 73 riveted to the insulating plate 56, and the pivot rivet 61 is connected by 25 a similar thin metal contact strip 74 to a contact terminal 75 also riveted to the insulating plate 56. The strips 72 and 74 and the heads of the rivets 61, 70, and 71 and the rivets of the terminals 73 and 30 75 are all located between the two insulating plates 55 and 56, and thus separated from the casing 15 by the insulating plate 55. In order to make certain that there is 35 always a firm and positive engagement between the switch lever 60 and the contact rivet 70, a spring finger 76 is riveted to the insulating plate 56, with the under head of its rivet also between the insulating plates 55 and 56, and the free end of the spring 40 finger 76 is so located that the edge of the switch lever 60 passes under it as the switch lever passes into engagement with the contact rivet 70, so that the spring action of 45 the finger 76 forces the switch lever 60 firmly against the rivet 70, as is clear from Fig. 7.

The terminals 25 and 73 are permanently connected by a wire 80. The terminals 24 and 42 are permanently connected by a wire 56 81. Thus the insulating plate 22 is fastened within the casing 15; but the wires 80 and 81 are of such length that the plate 22 can be shifted edgewise sufficiently to uncover either cell 16 or 17, to permit removal of 55 such cell. The terminals 42, 73, and 75 all project toward the center of the casing 15, as is clear from Figs. 1 and 2, and the plate 22 is located under such projecting parts, so that by the consequent overlapping of such 60 terminals with such plate, assisted by the wires 80 and 81, the cells 16 and 17 are held in position even though the lantern be inverted.

The terminal 75 is connected by a wire 82 65 to a terminal 83 which is detachably con-

nected to the binding post 84 of the carbon element of the cell 16. The wire 82 is so short that the terminal 83 cannot be placed on the binding post with the carbon element of the cell 17. The terminal 36 is connected 70 by a wire 85 to a terminal 86 which is detachably connected to the binding post 87 of the carbon element of the cell 17. By this arrangement of connections, it is impossible to connect the cells in any except the proper 75 relationship, for the terminals 24 and 25 which are fixed on the plate 22 can only be placed on the binding posts 24 and 25 of the zinc elements of the two cells, and when this is done the terminal 83 can only be placed 80 on the binding post 24 of the carbon element of the cell 16, leaving but one vacant binding post, the binding post 87 of the carbon element of the cell 17, for the terminal 86. 85

By reason of the connection described, the lamp bulb 39 is connected between the carbon element of the cell 17 and the zinc element of the cell 16, and the switch is connected between the carbon element of the 90 cell 16 and the zinc element of the cell 17. In other words, there is a cell between each side of the switch and the electrically adjacent side of the lamp bulb; and neither element of either cell is directly connected 95 to an element of the other cell. As a result of this, accidental short circuiting is impossible, for if some unforeseen connection arises, as between the two zinc elements of the two cells, there would be no 100 short circuit, but instead a resistance-containing circuit which would include either the normally open switch or the lamp bulb.

By reason of the two insulating plates 55 and 56 and the location of the rivet heads and connecting strips between them, and of the two insulating plates 29 and 30 and the location of the head of the rivet 43 between them, and of the washer 28 between the reflector housing 27 and the casing 15, and of the insulating bushing 32, the current-carrying parts are insulated from the casing 15, and such casing is prevented from becoming charged.

In addition to the handle 58, I provide a 115 carrying bail 90, which has inturned and flattened ends 91 longer in the plane of the bail than at right angles thereto. These in-turned ends 91 project through openings 92 in bell-shaped raised portions 93 which are 120 provided at the sides of the sheet metal casing 15, the holes 92 being longer horizontally than vertically, and of such dimensions that the ends 91 of the bail may slip in and out of the holes 92 when the bail is horizontal or are prevented from doing so when the bail is vertical. For strength, the holes 92 are lined with similarly shaped bushings 94, which prevent tearing out of the metal 125 around the holes. 130

By the term "lantern," as used in the specification and claims, I mean a light-emitting apparatus, whether of the kind ordinarily called "lantern" or of the kind ordinarily called "lamp"; and, unless otherwise specified, whether portable or stationary.

I claim as my invention:

1. In combination, two cells, a switch connected between the positive element of the first cell and the negative element of the second cell, and a lamp connected between the negative element of the first cell and the positive element of the second cell.
2. In a lantern, a casing of suitable size to receive two dry cells side by side, an insulating plate located to project over the edges of both dry cells and provided with perforated contact terminals fixed thereto to fit over the binding posts of the zinc elements of the two cells, thus requiring the cells to be in definite relative position in the casing, and contacts carried by opposite sides of the casing and permanently connected to the contacts on said plate.
3. In a lantern, a casing of suitable size to receive two dry cells side by side, and an insulating plate located to project over the edges of both dry cells and provided with perforated contact terminals fixed thereto to fit over the binding posts of the zinc elements of the two cells, thus requiring the cells to be in definite relative position in the casing.
4. In a lantern, a casing of suitable size to receive two dry cells side by side, an insulating plate located to project over the edges of both dry cells and provided with perforated contact terminals fixed thereto to fit over the binding posts of the zinc elements of the two cells, thus requiring the cells to be in definite relative position in the casing, and contacts carried by opposite sides of the casing and permanently connected to the contacts on said plate, said contacts carried by opposite sides of the casing projecting over the edge of said insulating plate.
5. In a lantern, a casing of suitable size to receive two dry cells side by side, an insulating plate located to project over the edges of both dry cells and provided with perforated contact terminals fixed thereto to fit over the binding posts of the zinc elements of the two cells, thus requiring the cells to be in definite relative position in the casing, contacts carried by opposite sides of the casing and permanently connected to the contacts on said plate, and terminals fixed on the sides of the casing and permanently connected by wires to terminals adapted to fit on the binding posts for the carbon elements of the two cells, one of the last-named terminals fixed on the casing being unequally distant from the binding posts for the carbon elements of the two cells and

the wire leading therefrom being so short that the terminal at the free end thereof can be placed on the binding post for the carbon element of one of the cells but can not be placed on the binding post for the carbon element of the other cell.

6. In a lantern, a casing of suitable size to receive two dry cells side by side, an insulating plate located to project over the edges of both dry cells and provided with perforated contact terminals fixed thereto to fit over the binding posts of the zinc elements of the two cells, thus requiring the cells to be in definite relative position in the casing, contacts carried by opposite sides of the casing and permanently connected to the contacts on said plate, and terminals fixed on the sides of the casing and permanently connected by wires to terminals adapted to fit on the binding posts for the carbon elements of the two cells.

7. In a lantern, a casing of suitable size to receive two dry cells side by side, and an insulating spacing plate loose within said casing and provided with perforations to fit over the binding posts of the zinc elements of the two cells, thus requiring such cells to be in definite relative position in the casing and preventing them from relative shifting.

8. In a lantern, a casing of suitable size to receive two dry cells side by side, an insulating spacing plate loose within said casing and provided with perforations to fit over the binding posts of the zinc elements of the two cells, thus requiring such cells to be in definite relative position in the casing and preventing them from relative shifting, contacts mounted on said insulating spacing plate at said perforations for engagement with said binding posts of the zinc elements, and connections leading from said contacts to attaching points on opposite sides of said casing.

9. In a lantern, a casing of suitable size to receive two dry cells side by side, an insulating spacing plate loose within said casing and provided with perforations to fit over the binding posts of the zinc elements of the two cells, thus requiring such cells to be in definite relative position in the casing and preventing them from relative shifting, and conductors attached to opposite sides of the casing and having free ends positioned by said conductors in approximate proper position for attachment to binding posts of the respective cells.

10. A lantern, comprising a casing of suitable size to receive two dry cells side by side, an electric lamp bulb mounted on the front of said casing, a switch on the back of said casing, connections for connecting said lamp bulb, switch, and dry cells in series, said connections including a flexible conductor mounted within said casing and

connected to said switch and a flexible conductor mounted within said casing and connected to said lamp, each of said two conductors having a free end which is normally in approximate position for attachment to binding posts of the two cells respectively, and an insulating spacing plate loose within said casing and arranged to project over the edges of both dry cells and to fit over the binding posts of the zinc elements of such cells, thereby requiring the cells to be in definite relative position in the casing.

11. A lantern, comprising a casing of suitable size to receive two dry cells side by side, an electric lamp bulb mounted on the front of said casing, a switch on the back of said casing, connections for connecting said lamp bulb, switch, and dry cells in series, said connections including a flexible conductor mounted within said casing and connected to said switch and a flexible conductor mounted within said casing and connected to said lamp, each of said two conductors having a free end which is normally in approximate position for attachment to binding posts of the two cells respectively, one of said conductors being attached to the casing at points unequally distant from the binding posts of the two cells and being so short that it can be fastened to a binding post of but one of such cells.

12. A lantern, comprising a casing of

suitable size to receive two dry cells side by side, a control switch, an electric lamp bulb mounted on said casing, and connections for connecting said lamp bulb, control switch, and dry cells in series, said connections including two flexible conductors within said casing and each rigidly supported at one point on said casing, said two conductors having free ends which are normally in approximate position for attachment to binding posts of the two cells respectively, and one of said conductors being attached to the casing at a point unequally distant from the binding posts of the two cells and being so short that it can be fastened to a binding post of but one of such cells.

13. In combination, two dry cells, a casing in which said two dry cells are adjacently mounted, a controlling switch, a lamp, and connections between the cells, the switch, and the lamp for connecting them in series, with one of the cells in the connection between each side of said switch and the lamp.

In witness whereof, I have hereunto set my hand at Indianapolis, Indiana, this eighteenth day of November, A. D. one thousand nine hundred and fifteen.

HOMER A. WOODS.

Witness:

H. P. WILLIAMS.
